UNITED STATES PATENT OFFICE.

CHARLES J. KLEIN, OF MILWAUKEE, WISCONSIN, ASSIGNEE TO THE CUTLER-HAMMER MFG. CO., OF MILWAUKEE, WISCONSIN, A CORPORATION OF WISCONSIN.

OUTLET-BOX.

1,153,394.

Specification of Letters Patent. Patented Sept. 14, 1915.

Application filed March 16, 1914. Serial No. 825,112.

To all whom it may concern:

Be it known that I, CHARLES J. KLEIN, a citizen of the United States, residing at Milwaukee, in the county of Milwaukee and State of Wisconsin, have invented new and useful Improvements in Outlet-Boxes, of which the following is a full, clear, concise, and exact description, reference being had to the accompanying drawing, forming part 10 of this specification.

This invention relates to electrical outlet boxes and the like. Such boxes are commonly set in plastered walls with their outer edges flush therewith. The boxes are also usually provided with cover-plates marginally overlapping the plastered surface. In practice, however, such cover-plates are positioned considerably after installation of the boxes, and during such interim the 20 plaster, thereabout is often accidentally chipped and broken or cracked by shrinkage, thereby presenting an unsightly appearance. Furthermore, it has been found that the plaster adheres poorly around the edges of 25 the box, thus necessitating a cover-plate materially larger than the box to conceal the raw edges of the plaster.

This invention has for its objects to provide an improved outlet box adapted to materially overcome the liability of shipping or cracking of a contiguous plaster surface.

In order to more clearly disclose my invention I have illustrated two embodiments thereof in the accompanying drawing, 35 wherein,

Figure 1 is a perspective view of one form of outlet box; Fig. 2 is a sectional view of one wall of the box shown in Fig. 1, showing in addition the box margin flush with a 40 cementitious surface; and, Fig. 3 is an elevation of the second form of box.

The device shown comprises a conventionally shaped metallic receptacle 1 provided on opposite edges with lugs 2 for receiving 45 screws to hold an ornamental face plate in position as a cover. The receptacle is positioned in a wall with its outer edges 3 projecting approximately three-eighths of an inch so that the plaster finishing may be 50 applied smoothly around the box.

Referring more specifically to the draw-

ing, the projecting edges 3 of the box are provided with closely spaced irregularities to which the plaster is adapted to rigidly adhere. In Fig. 1 these irregularities are 55 shown as comprising corrugations 4, preferably flared slightly at their outer ends. In Fig. 3 the edges of the box are provided with numerous staggered apertures 5 adapted to receive particles of the plaster when 60 applied.

In both embodiments of the receptacle, the finishing material 6 of the wall closely conforms to the irregularities of the edges of the box and tenaciously grips the same, 65 thereby materially lessening the liability of chipping or cracking of the plaster. Accordingly, the size of cover-plates required for the box need be only slightly larger than the open end of the same, thus economizing 70 in the metal of such plates. Furthermore, the box may be installed without presenting an unsightly appearance which has heretofore been a serious objection thereto.

What I claim as new and desire to secure 75 by Letters Patent is:

1. As an article of manufacture, an electrical outlet box for plastered walls having its outer margin provided with a multiplicity of relatively small and abrupt irregularities for effecting close adhesion of 80 plaster thereto.

2. As an article of manufacture, an outlet box for plastered walls having numerous exterior irregularities adjacent its outer 85 edges, said irregularities being of small size and angularly abrupt with respect to the remaining surface of the box exterior and affording a gripping surface for plaster contiguous thereto.

3. As an article of manufacture, a rectangular outlet box having its outer margins corrugated, the corrugations being relatively small and presenting a rough area 90 to grip plaster contiguous thereto.

In witness whereof, I have hereunto subscribed my name in the presence of two witnesses.

CHARLES J. KLEIN.
